No. 613,768.

Patented Nov. 8, 1898.

W. K. KIGHT.
CAR COUPLING.

(Application filed Aug. 5, 1898.)

(No Model.)

UNITED STATES PATENT OFFICE.

WILLIAM K. KIGHT, OF POPLAR BLUFF, MISSOURI, ASSIGNOR OF ONE-HALF
TO HORACE D. WILLIAMS, OF SAME PLACE.

CAR-COUPING.

SPECIFICATION forming part of Letters Patent No. 613,768, dated November 8, 1898.

Application filed August 5, 1898. Serial No. 687,850. (No model.)

To all whom it may concern:

Be it known that I, WILLIAM K. KIGHT, a citizen of the United States, residing in the city of Poplar Bluff, county of Butler, State of Missouri, have invented a certain new and useful Improvement in Car-Couplers, of which the following is a full, clear, and exact description, such as will enable others skilled in the art to which it appertains to make and use the same, reference being had to the accompanying drawings, forming part of this specification, in which—

Figure 1 is a top plan view of my improved car-coupler. Fig. 2 is a vertical sectional view on line 2 2, Fig. 1. Fig. 3 is a similar view illustrating the moving parts in a different position. Fig. 4 is a side elevational view of my improved car-coupler; and Fig. 5 is a detail sectional view on line 5 5, Fig. 1.

This invention relates to a new and useful improvement in car-couplers, and particularly to that class known as "twin-jaw" or "Janney" type of couplers, wherein a pin or bolt is provided to hold the knuckle portion of the coupler in a locked position.

The objects of this present invention are to construct a simple, cheap, and effective coupler provided with means for holding the lock-pin in a raised position ready for coupling and to provide means coöperating with the lock-pin for throwing the inner end of the knuckle in the proper direction to place the coupler, after being uncoupled, in a position to be automatically coupled when contacting with the knuckle of the coupler of another car.

The essential features of this invention reside, first, in the novel construction of the slide-bar for holding the lock-pin in a raised position; second, in the novel construction of the rock-shaft, which is provided with suitable arms, one of which coöperates with a slot or groove in the upper end of the lock-pin, while the other coöperates with the inner end of the knuckle, whereby when the lock-pin is raised the inner end of the knuckle is forced to a proper position to be automatically coupled; and, finally, the invention consists in the novel construction, arrangement, and combination of the several parts, all as

will hereinafter be described, and pointed out in the claims.

In the drawings, A indicates the main member or head of the coupler proper, preferably formed of a metallic casting.

55

B indicates the knuckle, also preferably a casting, which knuckle is pivoted to the coupler-head A by a bolt or pin b.

C indicates the lock-pin, which is positioned in the coupler-head A, preferably by passing 60 through a suitable opening a in the upper face of the same and through a hollow space provided within said coupler-head, and when in a locked position said pin is supported by the bottom wall of the coupler-head.

65

The knuckle B is substantially a bell-crank lever—that is, it is provided with two arms or members b' and b'', the former, called the "nose," when in a locked position coöperating with a similar nose or member of a 70 coupler of another car when said cars are coupled together and by which one car is enabled to draw the other, as is well understood. The other arm or member b'', called the "tail," is designed to be retained behind the lock- 75 pin to hold the nose b' in its coupled position.

All the parts before mentioned are substantially of old and well-known construction, and further description of the same is deemed unnecessary.

80

D indicates what I have termed a "slide-bar," preferably placed to one side of the lock-pin C and preferably arranged to slide in an inclined opening a', formed in the upper side of the casting A, and when the 85 coupler is in a locked position, as seen in Fig. 2, the lower end of said slide-bar rests upon the upper face of the tail b'' of the knuckle and is out of alinement with the lock-pin. Upon the inner face of this slide-bar D, 90 and preferably near its lower end, is formed a notch d, designed to receive the nearest lower edge of the lock-pin and retain the same when said lock-pin is raised, permitting the tail b'' of the knuckle to be drawn from beneath the same, as is clearly illustrated in Figs. 3 and 5. When it is desired to uncouple, the tail b'' moves from beneath the slide-bar and said bar will of its weight slide downwardly until the notch d in the lower end 95 100

thereof is brought into alignment with the nearest lower edge of the lock-pin and in which lower position said slide-block is arrested in its downward movement by suitable 5 projections d' , formed on the uppermost edges of said slide-bar, which contact with suitable faces formed on each side of the upper edges of the opening a' , through which the slide-bar passes.

- 10 Upon the upper face of the coupler A and on opposite sides of the opening a are arranged lugs $a'' a'''$, their inner faces being of greater distance apart than the width of said opening a' , thereby forming a flat face on 15 each side of said opening, which flat face is somewhat below the upper face of said lugs and is the face before referred to upon which the lugs d' of the slide-bar D rest when said bar is in its downward position, and when 20 said slide-bar D is in position its upper end is below the surface of said lugs, which, together with the portion of metal which connects their inner ends, forms a housing for the same, thereby protecting said upper end 25 of said slide-bar.

Positioned in the lugs a'' and a''' is a rock-shaft E, one end of which is provided with means for preventing lateral movement of the same, and the other end of said rock-shaft is formed with a member approximately 30 at right angles thereto. This member I shall designate hereinafter by reference to its arms e and e' . The arm e , starting, we will say, from the rock-shaft proper and extending inwardly and upwardly at its inner end, is provided with a bent portion e'' , parallel to said rock-shaft, which bent portion enters and cooperates with a groove or slot c in the upper portion of the lock-pin C. The arm e' starts 35 from the rock-shaft and is bent downwardly outside the coupler, but sufficiently far away when the coupler is in a locked position to enable the same to be moved inwardly some distance, as will be hereinafter explained, 40 said arm e' being formed at its free end with an inwardly-extending portion e''' , which passes through an opening a'''' in the side of the coupler. This end e''' when the coupler is in a locked position rests upon the side 45 of the arm b'' of the knuckle, and when the lock-pin is raised by any suitable means the arm e , carrying the portion e'' , co-operating with the slot c , rocks the shaft E, which forces the arm e' , carrying the inwardly-extending portion e''' , toward the coupler. This 50 action causes the end of the inwardly-extending portion e''' to contact with the arm b'' and place under tension a spring e'''' , forming a part of arm e''' , and when the lock-pin clears 55 the tail b'' said spring will force the knuckle outwardly in an open or coupling position. This movement of the coupler is automatic with respect to the withdrawing of the lock-pin, and when said lock-pin is thus raised 60 the slide-bolt D falls into its proper position to support the same, as before described.

It will be understood by referring to Figs.

2, 3, and 5 that when the knuckle is rocked to its coupled position the tail b'' will pass under the lock-pin and co-operate with the 70 lower end of the slide-bolt, raising the same sufficiently far to be out of the path of the lock-pin, whereupon a continued movement of said arm b'' will clear the end of said lock-pin, allowing the same to descend by gravity 75 to a locked or coupled position in front of the tail b'' .

The rock-shaft E, aside from its function already described, answers as a guard to prevent the slide-bolt D from being accidentally 80 displaced, as it is directly in the path of the same in its upward movement. Preferably the upper end of said slide-bar is formed with a concavity to insure a full and complete movement of the same in an upward direction, 85 as is obvious.

I am aware that minor changes in the construction, arrangement, and combination of the several parts of my coupler can be made and substituted for those herein shown and 90 described without in the least departing from the nature and principle of my invention.

Having thus described my invention, what I claim, and desire to secure by Letters Patent, is—

1. In a car-coupler of the Janney type, the combination with a coupler-head, of a knuckle pivoted thereto, a lock-pin co-operating with the tail of said knuckle for retaining the same in a coupled position, and a slide-bar so arranged and positioned as to support said lock-pin in a coupling position, said slide-bolt being also so located as to be forced from its supporting position when the tail of the knuckle is moved in the proper direction for coupling, 100 thereby permitting said pin to assume its coupled position, substantially as described.

2. In a car-coupler of the Janney type, the combination with a coupler-head, of a knuckle pivoted thereto, a lock-pin co-operating with 110 the tail of said knuckle for retaining the same in a coupled position, and a slide-bar operating in a suitable opening in the coupler-head and arranged obliquely to the path of said lock-pin, whereby, when in a coupling position, it will be in such a position as to support the lock-pin by receiving the same in a notch formed in the lower end of said slide-bar, said slide-bar being also provided with flanges for limiting its inward movement, substantially 115 as described.

3. In a car-coupler of the Janney type, the combination with the knuckle and its lock-pin, of an externally-arranged lever pivoted to one side of said lock-pin, one arm of said 125 lever engaging a slot or groove in the upper end of the lock-pin, and the other arm of said lever engaging the knuckle to force the same outwardly whenever the lock-pin is raised to release said knuckle, substantially as described.

4. In a car-coupler of the Janney type, the combination with the knuckle and its lock-pin, of an externally-arranged lever which is

operated by a slot or groove in the upper end of the lock-pin to force the knuckle outwardly whenever the lock-pin is raised to release said knuckle, and a spring in which energy is stored by the movement of the lock-pin in clearing the knuckle, said energy being exerted upon the knuckle when said knuckle is free to move, substantially as described.

5. In a car-coupler of the Janney type, the combination with a coupler-head, of a knuckle pivoted thereto, a lock-pin coöperating with the tail of said knuckle for retaining the same in a locked position, an inclined slide-bar for suspending said lock-pin in an upward position when said knuckle is released by the same, and an externally-arranged lever for coöperating with a slot or groove in the upper end of said lock-pin and the tail of the knuckle, whereby when the lock-pin is raised, the knuckle will be forced to a position ready to be automatically coupled by contacting with a suitable counterpart, substantially as described.

6. In a car-coupler of the Janney type, the combination with a coupler-head, of a knuckle pivoted thereto, a lock-pin coöperating with the tail of said knuckle for holding the same in a locked position, a slide-bar, said slide-bar being so positioned and arranged as to support the lock-pin when the same is in a coupling position and to be raised or forced from its supporting position by the inward movement of the tail of the knuckle, and a means for coöperating with the lock-pin and the tail of said knuckle, whereby, the move-

ment of the knuckle is automatic with respect to the said lock-pin, when the coupler is uncoupled, substantially as described.

7. In a car-coupler of the Janney type, the combination with a coupler-head, of a knuckle pivoted thereto, a lock-pin coöperating with the tail of said knuckle for holding the same in a locked position, a slide-bar, said slide-bar being so positioned and arranged as to support the lock-pin when the same is in a coupling position and to be raised or forced from its supporting position by the inward movement of the tail of the knuckle, and a rock-shaft, one end of said rock-shaft being provided with a member forming the arms *e* and *e'*, said arm *e* coöperating with a slot *c* in the lock-pin, while the other arm *e'* operates upon the tail of the knuckle, said last-mentioned arm *e'* being provided with a spring portion *e'''*, whereby, when the lock-pin is raised, the rock-shaft causes the arm *e'* to be forced inwardly against the tension of said spring portion *e'''*, which exerts its power upon the tail of the knuckle, and after the lock-pin has released said knuckle, said spring portion will force the knuckle to a coupling position, substantially as described.

In testimony whereof I hereunto affix my signature, in the presence of two witnesses, this 25th day of July, 1898.

WILLIAM K. KIGHT.
